UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR FORK AND SPOON HANDLES.

Specification forming part of Design No. 6,219, dated October 22, 1872.

To all whom it may concern:

Be it known that I, HORACE C. WILCOX, of West Meriden, in the county of New Haven and State of Connecticut, have invented a new Design for Fork and Spoon Handle; and I do hereby declare the following, when taken in connection with the accompanying drawing and the letters of reference marked thereon, to be a full, clear, and exact description of the same, and which said drawing constitutes part of this specification and represents a top view.

This invention relates to a design for the handles of spoons and forks; and consists in the peculiar configuration of the handle, as shown in the accompanying drawing, and as

hereinafter described, starting from the bowl of the fork and expanding slightly to an enlargement, as at A, thence again gradually expanding toward the end to the offsets a, and thence curved to a point. This may be ornamented by tracery or not, that being no part of the design.

I claim as my invention—

The design for handle of spoons or forks, as herein described and shown in the accompanying drawing.

HORACE C. WILCOX.
